US0D1051766S

(12) United States Design Patent (10) Patent No.: US D1,051,766 S
(45) Date of Patent: * Nov. 19, 2024

(54) CRAFT

(71) Applicant: Chung-Lun Lee, Dong Guan (CN)

(72) Inventor: Chung-Lun Lee, Dong Guan (CN)

() Term: 15 Years

(21) Appl. No.: 29/944,517

(22) Filed: May 28, 2024

(30) Foreign Application Priority Data

Nov. 28, 2023 (CN) 202330778237.2

(51) LOC (14) Cl. 11-02

(52) U.S. Cl.

USPC D11/160; D11/128

(58) Field of Classification Search

USPC ... D11/117, 128, 129, 130, 131, 131.1, 132,
